AUTOMATICALLY OPERABLE PROJECTILE

William Louis Roessner, Chicago, Ill., assignor to
Bertha L. MacGregor, as trustee

Application May 29, 1939, Serial No. 276,281

9 Claims.

(Cl. 169—26)

This invention relates to automatically operable projectiles. The embodiment of the invention herein shown is adapted for installation in fire extinguishers for automatically shattering or otherwise opening the containers which hold the fire extinguishing chemical. However, the invention is well adapted for various purposes, such as automatically opening containers of various kinds, moving objects such as locking bolts, doors and other devices, making electrical contacts whereby mechanisms are actuated, and for other purposes which will be obvious from the following description.

The main object of the invention is to produce an automatically operable projectile which normally will remain inoperative and which will function forcefully and quickly when certain predetermined conditions exist.

Another object is to produce a device of the character described, provided with thermo-responsive restraining means for normally holding the parts in inoperative positions, which means are preferably, though not necessarily, enclosed, whereby they are protected from injury and unintentional releasing action.

Another object of the invention is to provide a specially shaped and constructed projectile, capable of shattering frangible material widely dispersing the contents, and capable of cutting and entering containers made of non-frangible materials to permit escape of the contents.

Another object is to confine the projectile so that its movement will be confined to a predetermined path.

35 In the drawings:

Fig. 1 is a vertical sectional view of an automatically operable projectile embodying my invention, installed in the handle of a fire extinguisher grenade, the upper portion of the grenade being broken away.

Figs. 2, 3, 4, 5 and 6 are horizontal sectional views, on an enlarged scale, taken in the planes of the line 2—2, 3—3, 4—4, 5—5 and 6—6, respectively, of Fig. 1.

45 Fig. 7 is a vertical sectional view of a modified form of automatically operable projectile embodying my invention.

Fig. 8 shows the device of Fig. 7 after the projectile has been automatically released.

50 Fig. 9 is a horizontal sectional view, taken in the plane of the line 9—9 of Fig. 7.

Fig. 10 is a fragmentary, vertical sectional view of a modified form of projectile head.

In that embodiment shown in Figs. 1 to 6, inclusive, the hollow cylindrical handle 10 of the

fire extinguisher grenade 11 is used to house the automatically operable projectile of my invention. The projectile comprises a hollow shell 12, preferably cylindrical but not necessarily so, and a head 13 having a central bore 14, the head being retained by a pin 15 which extends through the shell walls and head from one side to the opposite side. Preferably, the shell 12 extends upwardly beyond the head 13 and has pointed edges 16.

10 Adjacent the lower end of the shell 12 is a saddle which consists of a table 17 and depending legs 18, 18. The saddle may be shaped to fit within a cylindrical member such as the handle 10, or its table 17 may be square or rectangular in shape 15 to fit within a complementally formed support. In this embodiment the table 17 is circular, cut away at 19 and 20, apertured at 21, 21, and the depending legs 18 are arcuate, to fit the inside of the handle 10 to which they ultimately are rigidly secured by screws 22.

15 The shell 12 is not connected to the saddle 17 but it is held normally in edge abutting position relatively thereto by the means about to be described. A thermo-responsive retaining member 23 indicated as a whole at 23 extends through a slot 24 in the saddle table 17 and is looped over a pin 25 which extends through the shell 12 and head 13 parallel with and below the pin 15. The pin 25 preferably is threaded to fit internally 25 screw threaded bores in said shell and head. The thermo-responsive member 23 consists of a strip 30 of metal 26 such as copper or the like, formed to provide the loop 27, spread apart arms 28, 28, and intermediate parallel portions, as shown in 35 Fig. 1. The arms 28 are spaced apart by fusible material 29 in which are embedded short tubes 30 of less fusible material. One or more of such tubes 30 may be used.

40 To assemble the projectile 12—13 and saddle 17—18, I first place a strong coiled spring 31 in the shell 12, the upper end of the spring 31 bearing against the head 13 and the lower end against the table 17 of the saddle. The spring is compressed so that the lower edge of the shell 12 rests 45 on the saddle 17, and while thus held, the thermo-responsive device 23 is inserted into place in the slot 24 of the saddle and the pin 25 is screwed into the shell and head walls, through the loop 27 of the device 23, whereby the connected shell 12 and head 13 are held in predetermined position 50 relatively to the saddle. Finally the assembled device is inserted in the handle 10, and the saddle legs 18 are secured to the handle by the screws 22.

The fusible material 29 may be any suitable alloy, chemical salts, wax compounds and the like, which are thermo-responsive. The enclosure of the device 23 within the support 10 prevents 5 unintended or premature releasing of the projectile 12. When a predetermined temperature has been reached in the vicinity of the support 10, the fusible material 29 will be affected, aided by the air draft through the tubes 30, apertures 21, head 10 bore 14, and handle 10 as a whole, and the expansive power of the spring 31 will cause the arms 28 of the device 23 to be drawn through the slot 24 in the saddle 17, thus releasing the projectile shell 12 and head 13 and permitting them to be 15 thrust forcefully toward the grenade 11, as indicated in dotted lines in Fig. 1. The spring 31 is powerful, so that the projectile, when released, strikes a forceful blow on an object intended to be broken or moved, and after the blow has occurred, the projectile continues to exert pressure 20 against the object.

In Figs. 7, 8 and 9, the projectile parts 12 to 16, the saddle members 17, 18, and the thermo-responsive device 23 are constructed as heretofore 25 described, but between the spring 31 and shell 12, there are telescoping members 32, 33. The upper one 32 has an inturned flange 34 on its upper end and the lower one 33 has an inturned flange 35 on its lower end. The flange 34 rests on the spring 31 30 which carries the telescoping member 32 upwardly, as shown in Fig. 8, when the thermo-responsive device 23 has been released.

The provision of the members 32 and 33 is 35 especially valuable when the invention is mounted on a support 10 which does not serve as a housing for all the parts, as does the handle 10 in Figs. 1 to 6, inclusive. In Figs. 7 to 9, inclusive, the housing 10 is broken away, and it may be eliminated entirely. The saddle 17-18 may be secured 40 to any suitable support, in such position that the projectile shell 12 will face the container to be broken or entered or the object to be actuated.

In Fig. 10 I have shown a modified form of the 45 head end of a projectile in which the parts 13, 15 and 25 have been eliminated. In their place I use an internally screw threaded pin 36 which has a head 37 countersunk in the shell 12, and an externally screw threaded pin 38 whose head 39 is countersunk in the shell wall opposite the head 37 and whose body is screwed into the pin 36. The thermo-responsive member 23 is not shown in this view. For assembling the device, I use 50 any suitable tool for holding the spring compressed within the shell, beneath the intended place to be occupied by the pins 36-38, and then insert the thermo-responsive member 23 in the saddle 17. Then the pins 36-38 are inserted through the shell walls and loop 27 of member 55 23. Thus the pins 36-38 serve as a projectile head, as means for connecting the thermo-responsive member to the shell and for retaining the spring in compressed condition until the thermo-responsive member is released.

60 65 Changes may be made in details of construction without departing from the scope of my invention.

I claim:

70 75 1. An automatically operable projectile comprising a slotted support, a hollow projectable shell, a compressed coiled spring within the shell, a head fixed in the shell confining the spring in the shell between the head and the support while the shell is held on the support, a link extending through the slotted support into the shell, means

connecting one end of said link to the shell, and thermo-responsive means on the other end of the link normally preventing the link from passing through the slotted support into the shell, said link consisting of a narrow flat metal strip 5 formed into a pair of parallel members connected by a loop at one end and having spread apart arms at the other end, all of said thermo-responsive means being located and confined between said arms flush with the edges thereof. 10

2. An automatically operable projectile comprising an open ended tubular housing, a slotted support fixedly mounted in the housing transversely of the housing and inwardly of one end, a hollow projectable shell within the housing on 15 said support, a compressed coiled spring within the shell, a head fixed in the shell confining the spring in the shell between the head and the support while the shell is on the support, a link extending through the slotted support into the 20 shell, means connecting one end of said link to the shell, and thermo-responsive means on the other end of the link normally preventing the link from passing through the slotted support into the shell, said thermo-responsive means 25 being located in the tubular housing between the support and an open end of the housing, said link consisting of a narrow flat metal strip formed into a pair of parallel members connected by a loop at one end and having spread apart arms 30 at the other end, all of said thermo-responsive means being located and confined between said arms flush with the edges thereof.

3. An automatically operable projectile comprising a slotted support, a hollow projectable 35 shell, a compressed coiled spring within the shell, a head fixed in the shell confining the spring in the shell between the head and the support while the shell is held on the support, a link extending through the slotted support into 40 the shell, means connecting one end of said link to the shell, thermo-responsive means on the other end of the link normally preventing the link from passing through the slotted support into the shell, a pair of telescoping members surrounding the spring, each having an inturned flange engaging an end of the spring, said members moving telescopically between the shell head and the support when the link is released and the spring expands. 50

4. An automatically operable projectile comprising an open ended tubular housing, a slotted support fixedly mounted in the housing transversely of the housing and inwardly of one end, a hollow projectable shell within the housing on 55 said support, a compressed coiled spring within the shell, a head fixed in the shell confining the spring in the shell between the head and the support while the shell is on the support, a link extending through the slotted support into the 60 shell, means connecting one end of said link to the shell, thermo-responsive means on the other end of the link normally preventing the link from passing through the slotted support into the shell, said thermo-responsive means being located in the tubular housing between the support and an open end of the housing, a pair of telescoping members surrounding the spring, each having an inturned flange engaging an end of the 65 spring, said members moving telescopically between the shell head and the support when the link is released and the spring expands. 70

5. An automatically operable projectile comprising an open ended tubular housing, a slotted support fixedly mounted in the housing trans- 75

versely of the housing and inwardly of one end, a hollow projectable shell within the housing on said support, a compressed coiled spring within the shell, a head fixed in the shell confining the spring in the shell between the head and the support while the shell is on the support, a link extending through the slotted support into the shell, means connecting one end of said link to the shell, and thermo-responsive means on the other end of the link normally preventing the link from passing through the slotted support into the shell, said thermo-responsive means being located in the tubular housing between the support and an open end of the housing, said slotted support consisting of a table member having a centrally located slot communicating with a recess in one side of the table, and leg members at right angles to and at opposite sides of the table member connected to said tubular housing.

6. An automatically operable projectile comprising a support, a hollow projectable shell loose on the support, a compressed coiled spring within the shell, a link extending through the support into the shell, means extending through one end of the link and shell walls outwardly of the compressed spring, said means comprising an internally screw threaded pin countersunk in one side of the shell and an externally threaded pin countersunk in the other side of the shell and screwed into said first mentioned pin, and thermo-responsive means on the other end of the link normally preventing the link from passing through the support into the shell.

7. An automatically operable projectile comprising a slotted support, a tubular projectile shell having an air passage extending longitudinally therethrough in communication with the slotted support, a coiled spring within the shell substantially surrounded by the shell, a link extending through the slotted support into the shell, means connecting the link to the shell and holding the spring compressed between said connecting

means and the slotted support, and thermo-responsive means on the free end of the link normally preventing the link from passing through the slotted support into the shell, release of the thermo-responsive means allowing the spring to expand and causing the shell, the link and the connecting means to be moved forcibly away from the slotted support.

8. An automatically operable projectile comprising a slotted support, a tubular projectile shell having an air passage extending longitudinally therethrough in communication with the slotted support, a coiled spring within the shell substantially surrounded by the shell, a link extending through the slotted support into the shell, means connecting the link to the shell and holding the spring compressed between said connecting means and the slotted support, thermo-responsive means on the free end of the link normally preventing the link from passing through the slotted support into the shell, release of the thermo-responsive means allowing the spring to expand and causing the shell, the link and the connecting means to be moved forcibly away from the slotted support, an open ended housing surrounding the assembled parts aforementioned, and means connecting the slotted support to the housing.

9. An automatically operable projectile comprising a tubular shell arranged for longitudinal movement, a slotted support, the shell having an air passage therethrough in communication with said slotted support, a U-shaped link extending through said slotted support, a transverse member connecting the link to the shell, a spring surrounding the link and interposed within the shell between the transverse member and the slotted support, and fusible material secured to the free ends of the link releasably retaining the spring in compressed position.

WILLIAM LOUIS ROESSNER.
